PIPELINE FLOAT

William W. Wilson, Shreveport, La., assignor to Morton S. Adler, Des Moines, Iowa, a fractional part interest

Filed Sept. 17, 1969, Ser. No. 19,185

Term of patent 14 years

Int. Cl. D12—99

U.S. Cl. D71—1

FIG. 1 is a perspective view of a pipeline float showing my new design,

FIG. 2 is an end view thereof,

FIG. 3 is a side view thereof,

FIG. 4 is a top view thereof,

FIG. 5 is a bottom view thereof,

FIG. 6 is a perspective view of a pipeline float showing a second embodiment of my new design, and

FIG. 7 is a bottom view of the article in FIG. 6.

I claim:

The ornamental design for a pipeline float, as shown.
